SCRATCHING POST FOR A CAT

Lionel A. White, 2305 Penrose St.,
San Diego, Calif. 92110

Filed May 15, 1974, Ser. No. 470,172

Term of patent 14 years

Int. Cl. D30—99

U.S. Cl. D30—42

FIG. 1 is a perspective view of a scratching post for a cat showing my new design;

FIG. 2 is a left side elevational view; and,

FIG. 3 is a right side elevational view.

The portions of the interior walls not shown are plain and not ornamented.

I claim:

The ornamental design for a scratching post for a cat, as shown and described.
